UNITED STATES PATENT OFFICE

HAROLD C. HUDSON, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

TRIMMING APPARATUS

Original application filed May 19, 1924, Serial No. 714,347. Divided and this application filed July 3, 1930. Serial No. 465,725.

This invention relates to trimming apparatus and is herein illustrated as embodied in apparatus of the type disclosed in my co-pending application filed May 19, 1924, Serial No. 714,347, of which the present application is a division. The apparatus illustrated herein is designed to operate on the margins of the bottoms of outsoled shoes, more particularly welt-shoes, for the purpose 10 of producing "thin edges", which are especially desirable in the shank portions of women's shoes.

In the better grades of shoes for women, and even in shoes of lower grade, the appearance of lightness is desired, but is counteracted to some extent in welt-shoes and McKay shoes by a thick and heavy appearance of the marginal extensions of the bottoms. In welt-shoes the thick and heavy appearance is due in part to the character and thickness of the outsoles and in part also to the additional thickness of the welts. Accordingly, it is common to reduce the thickness of the bottoms of women's welt shoes along the inner 25 and outer edges of the shank portions from points near the ball lines to points at or near the breast line, this "shank-reducing" operation being prior to and independent of the final edge-trimming operation.

In addition to reducing the thickness of shank portions as above set forth, it is also common to reduce the width of the marginal extensions of the shank portions of shoe-bottoms.

With this shank-reducing operation in view, an object of the present invention is to provide improved trimming apparatus by which both the thickness and the width of the marginal extensions of shoe bottoms may be 40 more readily and more satisfactorily reduced than heretofore.

The apparatus herein illustrated as embodying the present invention in a machine for reducing the margins of the bottoms of 45 outsoled shoes comprises a rotary toothed cutter the teeth of which are provided with angularly related cutting edges arranged to sever stock from the lower face of the margin of a shoe bottom, some of the cutting edges being 50 arranged to form a trimmed surface parallel

to the upper face of the margin and others of the cutting edges being arranged to bevel the margin from the inner boundary of the aforesaid trimmed surface to the lower face of the margin. The outsoles of shoes of the types to which the invention relates are commonly provided with channels to receive the stitches by which the outsoles are secured, and are also commonly provided with flaps by which the outsole-stitches may be covered when the shoes are finished. Therefore, in accordance with common practice, the channel-flaps will be open or folded back when the margins of the shoe-bottoms are trimmed or reduced in thickness by the cutter described above, but will be closed upon the beveled and otherwise trimmed margins and secured thereto by an adhesive before the shoes are finished. As a result of forming a trimmed surface parallel to the upper face of the margin of the shoe-bottom and of laying the outer margin of the channel-flap against this trimmed surface the thickness of the two-ply margin thus formed is uniform from the outer boundary thereof to the outer boundary 55 of the beveled surface, and in this way some latitude is provided for subsequently performing an edge-trimming operation without cutting into the beveled portion of the margin or into the correspondingly inclined portion 60 of the channel-flap. Thus, after the edge of the shoe bottom has been finally trimmed the reduced portion or portions of the margin will be of uniform thickness throughout 65 their length even though the final edge-trimming cut may remove more stock at some points than at others.

To control the course of trimming cut of the margin-reducing cutter above described, the invention also provides means arranged to guide a shoe relatively to the cutter. In the embodiment of the invention herein illustrated the guiding means comprises two circular concentric shields between which the cutter is arranged, the perimeter of one of the shields being formed and arranged to run in the crease between the upper and the marginal extension of a shoe bottom, while the perimeter of the other shield is arranged to run on the lower face of the margin of the 70 75 80 85 90 95 100

outsole and on the root of the backwardly folded channel-flap. Thus, while the cutter is reducing the thickness of the margin of a shoe-bottom, one or both of the shields control the course of the trimming cut as the shoe is drawn past the cutter, the channel-flap shield serving to prevent the cutter from trimming too closely to the root of the channel-flap whenever the other shield fails to reach quite to the deepest point in the crease between the upper and the marginal extension of the shoe-bottom.

When the cutter above described is used on a welt-shoe, the beveling cut may intersect the upper face of the outsole inside the outer boundary of the welt, and may also, if the welt be relatively thick, intersect the lower face of the welt. Consequently, the trimmed surface that is formed parallel to the upper face of the marginal extension of the shoe-bottom will be formed on the welt, its inner boundary being coincident with the outer boundary of the beveled surface. Moreover, when this operation is performed on a welt-shoe, the beveling cut will place the outer boundary of the margin of the outsole some distance in from the outer boundary of the welt so that when the channel-flap is subsequently laid against the beveled margin of the outsole it will project beyond the outer boundary thereof and will lie in direct contact with the lower face of the welt. The margin of the welt and the margin of the channel-flap will then form a two-ply margin susceptible of being reduced in width by a subsequent edge-trimming operation without uncovering or exposing the edge of the beveled margin of the outsole.

The illustrated shield that runs in the crease between the upper and the marginal extension of the shoe-bottom is provided with a flat face confronting the cutting edges by which the lower face of the marginal extension is trimmed parallel to the upper face thereof, this flat face of the shield being parallel to and spaced from the cutting edges just mentioned and serving to brace the margin of the extension against them to insure uniform thickness of the reduced marginal extension. Moreover, the illustrated cutter is also provided with cutting edges arranged to reduce the width of the marginal extension by trimming the outer edge thereof sufficiently to enable the channel-flap, when the latter is subsequently closed, to reach approximately to the outer edge above mentioned. In a welt shoe this outer edge would, of course, be the outer edge of the welt.

Referring to the accompanying drawings, Fig. 1 is a longitudinal section on an enlarged scale of a cutter mechanism embodying the features of the present invention in the act of operating on the shank portion of an outsoled welt-shoe, the outsole of which is channeled;

Fig. 2 is a perspective view of the individual elements of the cutter mechanism illustrated in Fig. 1;

Fig. 3 is an end elevation of the cutter element of said mechanism;

Fig. 4 is a cross-sectional view of a shank portion of a welt-shoe corresponding to the portion included in Fig. 1 but illustrating the condition of the welt and the margin of the outsole before they are trimmed as illustrated in Fig. 1; and

Fig. 5 is a similar view showing the result of trimming the welt and the margin of the outsole as aforesaid and of closing the channel-flap on the portions so trimmed.

It may be assumed that the outsoled welt-shoe, represented in Figs. 1, 4 and 5, is made according to any well-known procedure to and including the usual rough-rounding and channeling operation, which operation trims the outer boundaries of the outsole and the welt approximately to the final contour to be imparted to them subsequently to the trimming operation with which this invention deals. The outsole 2 is provided with a channel 3 for the outsole stitches and with a channel-flap 6 by which these stitches will be covered when the flap is closed after the outsole-stitching operation has been performed. The welt indicated at 4 lies against the upper face of the margin 5 of the outsole and is connected thereto by an adhesive with which these elements are commonly coated prior to laying the outsole. The rough-rounding operation, which follows the attaching of the outsole as aforesaid, trims the outer boundaries of the welt 4 and the margin 5 of the outsole flush with each other as represented in Fig. 4, and the channeling operation, which is commonly performed simultaneously with the rough rounding, forms the channel 3 and the channel-flap 6.

A shoe that has progressed to the condition represented in Fig. 4 is ready for the outsole-stitching operation by which the outsole is secured to the welt 4 by stitches located as illustrated by the outsole-stitch 7 in Fig. 5. This stitching operation may be performed before or after the marginal-trimming operation to which this invention relates, some manufacturers preferring to stitch the outsole before the marginal-trimming operation is performed to obtain the advantage of a more secure connection between the outsole and the welt than the connection afforded by adhesion only, but the marginal-trimming operation may be performed prior to the outsole-stitching operation with satisfactory results provided the adhesive bond between the welt and the margin of the outsole is strong enough to hold the outsole securely while the marginal-trimming operation is being performed.

Fig. 4 includes dotted lines that indicate how and to what extent the welt 4 and the

margin 5 of the outsole will be reduced by the cutter mechanism illustrated in Fig. 1. The oblique dotted line 8 represents the plane on which the margin 5 will be beveled from a line adjacent to the stitch-receiving channel 3 to a line on the upper face of the margin 5 inside the outer boundary of the welt. If the welt 4 is as thick as represented, this beveling cut will also intersect its lower face, but in no case will it extend to the opposite face of the welt. From the outer boundary of the beveling cut represented by the line 8, the trimming cut extends in a plane parallel to the upper face of the welt (see dotted line 9) to insure that the outer margin of the welt shall be of uniform thickness for a reason that appears at a later point in this description. If desired, the welt may also be trimmed at right angles to the line 9 to reduce its width as indicated by dotted line 10. Thus, whether or not the width of the welt is reduced, the beveling cut represented by the line 8 places the outer boundary of the trimmed margin 5 well inside the outer boundary of the welt 4 so that when the channel-flap 6 is subsequently closed as illustrated in Fig. 5, it will project beyond the outer boundary of the beveled margin of the outsole and will lie in direct contact with the lower face of the welt to which it will be secured by an adhesive. Moreover, the trimming cut represented by the dotted line 9, being parallel to the upper face of the welt, will remove any thick spots or fuzz from the flesh side of the welt and thus insure uniform thickness of the two-ply margin comprising the welt and the channel-flap 6, which margin may be subsequently trimmed more closely to the welt-crease without uncovering or encountering the interposed beveled margin of the outsole. In this way provision is made for a final edge-trimming operation by which a very thin marginal extension of the shoe-bottom may be trimmed even more closely to the welt-crease without cutting into the inclined portion of the closed channel-flap or into the beveled margin of the outsole covered thereby.

Referring to Figs. 1, 2 and 3, the present invention provides an improved cutter mechanism for reducing the thickness and the width of the marginal extensions of shoe bottoms in accordance with the foregoing explanation. This mechanism comprises a rotary toothed cutter having cutting teeth 46 projecting outwardly from a hub 44 and tapering to thin edges at their tips. The cutting teeth are arranged between two confronting work-guiding members shown as circular shields 48 and 60, the shield 48 being formed and arranged to run in the welt-crease of the shoe as illustrated in Fig. 1, and the perimeter of the shield 60 being arranged to run on the outsole at the junction of the margin 5

and the root of the channel-flap 6, as shown in that figure.

The rear face 74 of the shield 48 is flat and lies in a plane perpendicular to the axis of the cutter mechanism. This face is arranged to engage the upper face of the welt 4 to brace the welt against the front faces of the cutting teeth 46 the cutting edges 68 of which are formed and arranged to sever stock from the lower face of the welt in a plane parallel to the upper face thereof (see dotted line 9 in Fig. 4). The perimeter of the shield 48 projects beyond the outer boundary of the flat face 74 and is preferably concaved or relieved as indicated at 76 to avoid being wedged too tightly into the welt-crease and thus interfering with the movement of the shoe past the cutter. This shield 60 lies against the rear faces of the teeth 46 which are preferably flat, and projects slightly beyond the tips of the teeth. Its perimeter is preferably provided with a bead 62 which prevents the beveling cut from reaching quite to the root of the channel-flap and also, if the outsole has been previously stitched to the welt, guards the outsole stitches 7 in the channel 3 from attack by the cutter. The bead 62 is interrupted or divided into segments as illustrated in Fig. 2 to provide gaps 64 into which the tips of the cutting teeth 46 may project.

In addition to the cutting edges 68 which lie in a plane perpendicular to the axis of the cutter mechanism, the front faces of the teeth 46 are provided with inclined cutting edges 66 which are formed and arranged to reduce the width of the margin 5 of the outsole with a beveling cut that intersects the upper face of the outsole and in some cases also the lower face of the welt as indicated by the dotted line 8 in Fig. 4. These inclined cutting edges 66 adjoin the perpendicular cutting edges 68.

When the described parts are assembled, the perpendicular cutting edges 68 are spaced from the confronting face 74 of the shield 48 by a portion of the cutter. The space thus provided limits the thickness that the margin of the welt may have after it has been trimmed. The width of this space may be, and in many cases will be, less than the initial thickness of the welt, since welts vary in thickness as well as in width. Thus, when thicker welts are used the cutting edges 68 will reduce the thickness of their margins and still leave greater thickness elsewhere.

The illustrated cutter is also provided with cutting edges 70 which extend from the cutting edges 68 to the flat face 74 of the shield 48 at right-angles thereto and parallel to the axis of the cutter mechanism. The cutting edges 70 are arranged to reduce the width of the welt 4 by trimming the outer edge thereof so that when the channel-flap 6 is subse-

quently closed as illustrated in Fig. 5, its edge will be approximately, if not quite, flush with the trimmed edge of the welt. However, in certain aspects, the invention is not dependent upon providing the cutting edges 70, since, even if the welt does project beyond the channel-flap after the latter has been closed, it will be subsequently trimmed by another cutter mechanism which will be used in every case to perform the final edge-trimming operation.

Any suitable means may be provided to support and rotate the cutter and the shields hereinbefore described, the means shown in Figs. 1 and 2 being well-known elements of edge-trimming machines heretofore in use. As shown, the hub 44 of the cutter is mounted on an expandable, kerfed, steel thimble 40 having a flange 42 at its rear end. This thimble is internally tapered and is arranged upon a portion 38 of like taper formed on a rotary cutter-shaft 30.

The shield 48 abuts against the forward end of the hub 44 of the cutter and is provided with a circular shoulder 50 that fits the bore of the hub to centralize the shield. A headed screw 52 extends through a hole in the center of the shield 48 and into a screw-threaded socket in the center of the shaft 30. As the screw 52 is screwed home it forces the shield 48 against the hub 44 of the cutter, the axial movement of the cutter being transmitted to the flange 42 of the expandable thimble which is thereby forced toward the larger end of the tapering portion 38 of the shaft. The thimble 40 is thus expanded tightly against the bore of the cutter and, in addition, the cutter is clamped by the shield 48 and the flange 42 of the thimble.

The shield 60, which lies against the flat rear faces of the cutter teeth 46, is shown as a thin, flat ring of sheet metal, copper being suitable for this purpose. It is backed or braced by a stronger and thicker ring 58 of steel, brass or other metal. This shield and its backing ring 58 are both carried by a sleeve 34 that surrounds the shaft 30 and is secured thereto by a set-screw 36, the sleeve being axially adjustable to provide for placing the shield against the backs of the teeth 46. A peripheral flange or shoulder 56 formed on the sleeve 34 abuts the rear end of the backing ring 58 to maintain the shield 60 in contact with the rear faces of the cutting teeth 46. The interior of the sleeve 34 is counterbored or relieved as indicated at 54 to clear the hub 44 of the cutter.

In using the described cutter mechanism, the operator manipulates a shoe in substantially the same manner as for ordinary edge-trimming, that is, by raising the shoe to press the welt and the margin of the outsole against the under portion of the trimming cutter until the upward movement of the shoe is arrested by the shield 48 or the shield

60 or by both, and by drawing the shoe edge-wise past the cutter. If the shoe is rocked while it is being drawn past the cutter, at least one of the shields will maintain control of the shoe to prevent the beveling cut from extending too far toward the root of the channel-flap, but more commonly both of the shields will share in controlling the course of the trimming cut provided the location of the outsole channel has been properly located with respect to the welt-crease. However, no particular problem arises with respect to properly locating the outsole channel if the latter is cut with a rough-rounding and channeling machine after the outsole has been attached to a shoe, since modern machines for that operation locate the outsole channel with sufficient accuracy to insure uniform and satisfactory results from the herein-described shank-reducing cutter mechanism.

Having described my invention, what I claim as new and desire to secure by Letters Patent of the United States is:—

1. In a machine for trimming the margins of the bottoms of outsoled shoes, a rotary toothed cutter the teeth of which are provided with angularly related cutting edges arranged to sever stock from the lower face of such a margin, some of said edges being arranged to form a trimmed surface parallel to the upper face of the margin and others of said edges being arranged to bevel the margin from the inner boundary of said trimmed surface to the lower face of the margin, and means arranged to guide a shoe relatively to said cutter.

2. A rotary toothed cutter having angularly related cutting edges arranged to sever stock from the lower face of the margin of the bottom of an outsole, some of said edges being arranged to form a trimmed surface parallel to the upper face of said margin, and others of said edges being arranged to bevel the margin from the inner boundary of said trimmed surface to the lower face of the margin.

3. In a machine for trimming the margins of the bottoms of outsoled welt-shoes, a cutter mechanism comprising cutting means formed and arranged to reduce the width of the margin of the outsole with a beveling cut that intersects the contacting faces of the outsole and the welt, and means arranged to reduce the thickness of the margin of the welt by severing stock from the lower face thereof in a plane parallel to the opposite face of the welt.

4. In a machine for trimming the margins of the bottoms of outsoled welt-shoes, cutting means formed and arranged to reduce the width of the margin of the outsole by beveling the lower face of said margin with a cut that intersects the upper face thereof, cutting means formed and arranged to reduce the

thickness of the margin of the welt by severing stock from the lower face thereof, and means arranged to engage the upper face of the welt to brace the margin thereof against 5 the latter said cutting means.

5. In a machine for trimming the margins of the bottoms of outsoled welt-shoes, cutting means formed and arranged to reduce the width of the margin of the outsole by 10 beveling the lower face of said margin with a cut that intersects the upper face thereof, cutting means formed and arranged to reduce the thickness of the margin of the welt by severing stock from the lower face thereof, 15 means arranged to engage the upper face of the welt to brace the margin thereof against the latter said cutting means, and means arranged to engage the outsole at the junction of its margin and the channel-flap to guide 20 the work past said cutting means.

6. In a machine for trimming the margins of the bottoms of outsoled welt-shoes, a cutter mechanism comprising means arranged to reduce the width of the margin of the welt, 25 means arranged to reduce the width of the margin of the outsole to a greater extent than the reduction of the welt as aforesaid, with a beveling cut that intersects the contacting faces of the welt and the outsole, and 30 means arranged to reduce the thickness of the margin of the welt by severing stock from the lower face thereof in a plane parallel to the opposite face of the welt.

7. In a machine for trimming the margins 35 of the bottoms of outsoled welt-shoes, a rotary cutter-shaft, a toothed cutter carried thereby, said cutter having inclined cutting edges formed and arranged to bevel the margin of a channeled outsole from a line adjacent to the root of the channel-flap to a line on the welt-engaging face of said margin inside the outer boundary of the welt, and also having cutting edges perpendicular to the cutter-axis formed and arranged to trim the 45 lower face of the welt between the latter said line and said boundary of the welt, and means arranged to engage the upper face of the welt to brace the latter against said perpendicular cutting edges.

8. In a machine for trimming the margins 50 of the bottoms of outsoled welt-shoes, a rotary cutter-shaft, a toothed cutter carried thereby, said cutter having right-angularly related cutting edges formed and arranged to trim the outer boundary and the lower face of the margin of a welt, and also having inclined cutting edges formed and arranged to bevel the margin of a channeled outsole from a line inside the trimmed boundary of the welt to a line adjacent to the root of the channel-flap, and means arranged to engage the upper face of the welt to brace the welt against said cutting edges by which the lower face of the welt is trimmed.

9. In a machine for trimming the margins

of the bottoms of outsoled welt-shoes, a rotary cutter-shaft, and a trimming mechanism carried thereby and comprising two circular shields and a toothed cutter interposed between them, the perimeter of one of said shields being formed and arranged to run in the welt-crease of a shoe and that of the other being formed and arranged to run on the junction of the margin and the channel-flap of the outsole, the teeth of said cutter being tapered to thin edges at their tips and having inclined cutting edges confronting but spaced from said welt-crease shield to bevel the lower face of the margin of the outsole.

10. In a machine for trimming the margins of the bottoms of outsoled welt-shoes, a rotary cutter-shaft, and a trimming mechanism carried thereby and comprising two circular shields and a toothed cutter interposed between them, the perimeters of said shields being formed and arranged to run respectively in the welt-crease of a shoe and on the root of an open channel-flap of an outsole attached to the shoe, said cutter having cutting edges confronting but spaced from the inner face of said welt-crease shield to trim the lower face of the welt, and also having inclined cutting edges formed and arranged to bevel the margin of the outsole from a line inside the outer boundary of the welt to a line adjacent to the root of the channel-flap.

11. In a machine for trimming the margins of the bottoms of outsoled welt-shoes, two confronting work-guiding members spaced apart and arranged to run one in the welt-crease and the other on the margin of a channeled outsole and also on the root of the channel-flap, and a cutter mechanism comprising cutting teeth arranged to function between said members, said cutting teeth being tapered but having flat rear faces against which said other one of said work-guiding members lies, the front faces of said cutting teeth having inclined cutting edges arranged to bevel the lower face of the margin of the outsole.

12. In a machine for trimming the margins of the bottoms of outsoled welt-shoes, a rotary cutter mechanism comprising a cutter-shaft, a toothed cutter, two circular confronting work-engaging members between which the teeth of said cutter lie, one of said members being arranged to engage the upper face of the welt, the teeth of said cutter being tapered toward their tips and having inclined cutting edges to bevel the lower face of the margin of the outsole, and means arranged to space said inclined cutting edges from said welt-engaging member, the other one of said circular members being arranged against the backs of the tips of the cutter teeth and its perimeter being arranged to run on the mar-

gin of the outsole and on the root of the channel-flap.

13. In a trimming machine, a rotary cutter-shaft and a cutter mechanism carried thereby, said mechanism comprising a toothed cutter the teeth of which taper toward their tips, and two circular concentric shields between which said teeth are arranged, one of said shields being formed and arranged to run on the upper and on the marginal extension of the bottom of an outsoled shoe while said teeth bevel the lower face of the margin of the outsole, and the other one of said shields being formed and arranged to run on the outsole at the junction of said margin and the channel-flap.

14. In a machine for trimming the margins of the bottoms of outsoled shoes provided with welts and channeled outsoles, a cutter mechanism comprising means formed and arranged to reduce the width of the margin of the outsole by beveling the lower face of said margin with a cut that intersects the upper face of said margin, and cutting means formed and arranged to reduce the thickness of the margin of the welt by severing stock from the lower face thereof.

15. In a machine for trimming the margins of the bottoms of outsoled shoes provided with welts and channeled outsoles, a cutter mechanism comprising means formed and arranged to reduce the width of the margin of the outsole by beveling the lower face of said margin with a cut that intersects the upper face of said margin, and cutting means formed and arranged to reduce the width of the margin of the welt without beveling the welt.

In testimony whereof I have signed my name to this specification.

HAROLD C. HUDSON.
